UNITED STATES PATENT OFFICE.

WILLARD IRVING TWOMBLY, OF NEW YORK, N. Y., ASSIGNOR TO TWOMBLY MOTORS COMPANY, OF NEW YORK, N. Y., A CORPORATION OF NEW YORK.

INTERNAL-COMBUSTION ENGINE.

1,131,296.

Specification of Letters Patent. Patented Mar. 9, 1915.

Application filed December 18, 1911. Serial No. 666,617.

To all whom it may concern:

Be it known that I, WILLARD IRVING TWOMBLY, a citizen of the United States, residing in the borough of Manhattan, in the city, county, and State of New York, have invented new and useful Improvements in Internal-Combustion Engines, of which the following is a specification.

This invention relates to internal combustion engines in which during a single revolution of the crank shaft there is a compression of combustible mixture or fuel, a power stroke as the result of the combustion of said compressed fuel, the exhaust of the spent gases of combustion from said chamber, and the supplying of a fresh charge of combustible material or fuel; and it is the primary object of the invention to improve the general construction and operation of an engine of this type.

It is a further object of the invention to provide an engine of this type with two cylinders, each cylinder comprising a combustion chamber and a fuel pumping and compression chamber, and to provide means connected with the source of fuel supply to connect the fuel pumping chamber of the one cylinder with the combustion chamber of the other cylinder, and to provide mechanically operated valve mechanism to control the supply of fuel to the fuel pumping chambers.

A further object of the invention is to provide means whereby to effect a thorough scavenging of the products of combustion from the combustion chamber, and for which purpose an air pumping and compression chamber is provided for each of the cylinders which are connected with the combustion chambers as the exhaust ports are uncovered and the pistons approach the end of the power-stroke and previous to the supplying of a fresh charge of combustible mixture to the combustion chamber.

Further objects and advantages will hereinafter appear.

In the drawings accompanying and forming a part of this specification, Figure 1 is a sectional side elevation of my improved engine, the section being taken substantially through the middle of the same. Fig. 2 is a sectional side elevation of the means to connect the combustion chamber of one cylinder with the fuel-pumping chamber of the other cylinder, and the valve mechanism to

control the charge of fuel to the fuel pumping chambers, the section being taken substantially on the line A—A of Fig. 4. Fig. 3 is a plan view. Fig. 4 is a sectional front elevation taken substantially through the middle of the cylinder at the left of Fig. 1, and Figs. 5 and 6 are sectional detail views of the valve mechanism to control the charge of fuel to the fuel-pumping chambers.

Similar characters of reference designate like parts throughout the different views of the drawings.

The embodiment of my invention illustrated in the drawings, comprises a casing 1 in which is journaled a crank shaft 2, which casing may be provided with lateral arms or hangers 3 having rollers 4 on the extremities thereof, whereby when the engine is utilized as the motive power for a motor vehicle it is mounted in the frame of the motor vehicle to be readily placed theron and removed therefrom. A pair of cylinders *a*, *b*, are secured to the crank case, said cylinders in the present instance consisting of superposed sections 8, 9, the upper sections 8 being of less diameter than the lower sections 9 and constituting combustion chambers *c* having fuel-intake ports 16 and exhaust ports 17, while the enlarged portions 9 constitute fuel pumping and compression chambers *d*, having fuel intake and outlet ports 18. The cylinder sections are secured to the crank case by tie-rods 10 passing through flanges 11 projecting laterally from the cylinder sections 8. The cylinder sections 8 have a portion projecting into the sections 9 to compensate for the travel of the pistons 12, whereby the pistons may have a long stroke without unduly lengthening the cylinders, as clearly shown in Figs. 1 and 4. The casing 1 is provided with a wall or partition 5 separating it into two compartments, and when the cylinders are secured thereto that portion of the cylinder sections 9 below the pistons in connection with the compartments in the crank case constitute separate chambers *e*, *e*, having no communication with each other, and for a purpose to be hereinafter described. It will be noted that the cylinder sections 9 rest directly upon the case, and that the cranks of the shaft as they pass through their orbit of movement swing through the lower portion of said cylindrical sections.

said sections having outwardly bulging portions, as at 7, to permit of the passage of the cranks thereby making a very compact construction.

5 Duplex pistons 12 are connected to the crank shaft 2 by rods 13 to operate in the respective cylinders, each piston having an enlarged portion or an auxiliary head to operate in the enlarged portions 9 of the cylinders and separating the fuel-pumping chambers *d* from the crank case. Both piston heads are provided with packing rings to seal the combustion chambers from the fuel-pumping chambers, and to seal the latter from the crank case, and are also provided with the usual oil grooves.

It will be noted that as thus constructed the fuel pumping chamber has no communication with the crank case and that the 10 power stroke of the piston also serves as the fuel-pumping stroke, and as a charge of fuel is compressed in the combustion chamber 8 of a cylinder the fuel is also compressed in its fuel-pumping chamber. The fuel-pumping chamber of the one cylinder, as for instance *a*, is connected with the combustion chamber of the cylinder *b*, and the fuel-pumping chamber of the cylinder *b* is connected to the combustion chamber of the cylinder *a*, for which purpose I provide a fuel chest (designated in a general way by *F*) connected to the source of fuel supply, and provided with a pair of chambers 14, 15, and which also serve as fuel compression chambers to relieve the fuel pumping chambers of the high fuel compression pressures. The chamber 14 is provided with a port 19 communicating with the port 18 of the fuel-pumping chamber *d* of the cylinder *a* and a port 20 communicating with the fuel-intake port 16 of the combustion chamber *c* of cylinder *b*, while the chamber 15 is provided with a port 21 communicating with the port 18 of the fuel-pumping chamber *d* of cylinder *b* and a port 22 communicating with the fuel intake port 16 of the combustion chamber *c* of cylinder *a*.

The charge of fuel to the pumping chambers and combustion chambers is controlled 50 by mechanically operated valve mechanism, comprising a valve chest 23, in the present instance fixed to the chamber *F* although it may be constructed integral therewith, having a bore extending therethrough in which is mounted a tubular member or valve 24 to have oscillatory movement, and maintained against endwise movement by caps 25, 26 secured in the ends of the bore, and to the cap 26 may be connected a carbureter, as at 27. The chest 23 is provided with ports 28, 29 communicating with ports in the chambers 14, 15, respectively, to connect them with the carbureter or other source of fuel supply. The valve 24 is provided with 65 a pair of posts 30, 31 which register with the

respective ports 28, 29 at predetermined points in the oscillations thereof to connect and disconnect the chambers 14, 15 and the fuel pumping chambers to the source of fuel supply, as will be hereinafter described.

The valve 24 is operated from the crank shaft by means of an eccentric 32 fixed to the shaft, and a rod 33 connected at one end to a separable strap 34 surrounding the eccentric, the other end connected to a crank 35 fixed to a shank 36 passing through the cap 25 and having an enlarged portion 37 engaging in, and whereby it has an air tight connection with, the valve 24. A series of balls 38 may be interposed between the strap 34 and the periphery of the eccentric 32.

Each of the cylinders *a*, *b*, is provided with an air pumping and compression chamber *e* below the pistons formed by the cylinder sections 9 and the compartments in the crank case, as already stated. Each of the chambers (in the present instance located in the cylinder sections 9,) is provided with an air-intake port 39 having a valve 40 which is normally maintained closed by a spring 41. As the pistons compress a charge of fuel in the combustion and fuel-pumping chambers the suction of the pistons will unseat the valves 40 drawing in a charge of air which is compressed during the power stroke of the pistons, the pistons having a port 42 which will register with a by-pass port 43 in the inner wall of the cylinder sections 8 immediately after the pistons begin to uncover the exhaust ports and previous to the uncovering of the fuel-intake ports 16, whereby to connect the combustion chambers with the air chambers and the compressed charge of air below the pistons in the chambers *e* is injected into the combustion chamber expelling the products of combustion therefrom.

The cylinders are water cooled, and for this purpose I provide sheet metal jackets 44 preferably made of light spun copper surrounding the heads of the cylinders and spaced therefrom to form water chambers 45. The jackets are snugly fitted upon an annular seat 46 in the cylinder flanges 11, and have shrunk thereover steel rings 47 so as to form water-tight joints. The heads of the jackets are provided with perforations or openings for the passage of bushings 48 screw threaded into bosses projecting from the heads of the cylinders, and in which are secured spark plugs 49 carrying the terminal points of an electrical ignition system to ignite the charge of fuel in the combustion chambers. The bushings 48 have an annular flange between which flange and the piston boss the edges of the openings in the jackets are clamped in water-tight connection. To maintain a circulation of water through said jackets I connect an inlet pipe 50 to the water chamber, as at 130

51, leading from the source of water supply, such as a radiator or a cooler. (Not shown). An outlet pipe 52 is connected to the water jacket, as at 53, leading to the cooler, the circulation being maintained either by a suitable pump or the thermosiphonic system.

To lubricate the pistons and other operative parts of the engine, I provide a lubricant distributing reservoir 54 in the bottom of the crank case, conduits 55 leading from said chamber to the walls of the cylinders, as at 56, and the valve chest, as at 57, needle valves 58 being provided in the conduit connections to regulate the flow of lubricant. Ducts 60 lead from said chamber to the bearings of the crank shaft the upper ends of which ducts are formed with enlarged pockets 61, the ducts being normally closed by gravity seated balls 62 in said pockets. When the bearings of the crank shaft are provided with bushings, as in the present instance, they are provided with oil holes communicating with the pockets 61. Communication between the chambers 54 and e is normally shut off by valves 63 normally seated by springs 64 in a nipple 65 projecting up into the chambers e, with the stems of the valves slidably supported in plugs 66 secured in the bottom of the chamber 54, articulated sleeves 67 confined between the plugs 66 and nipples 65 serving to guide and support the valves. The lubricant is forced to the cylinder walls and crank shaft bearings by means of the compressed air in the chambers e during the power strokes of the pistons. As the air is compressed in the chambers e it will pass through the nipples 65 unseating the valves 63 and pass through the articulations in the sleeves 67 thereby forcing the lubricant in chamber 54 up through the conduits 55, 60, to the cylinders and bearings. As soon as the pressure is reduced in the chambers e, or during the fuel compression strokes of the pistons, the valves will be seated by the springs 64 shutting off communication between the chambers e and 54 and preventing the sucking of the lubricant through the nipples 65 into the chambers e. It will be noted that the nipple 65 projects somewhat up into the chambers e, any surplus lubricant which drips from the bearings collecting in the bottom of the chambers e, and as the crank shaft revolves it will be splashed by the cranks up against the walls of the cylinder sections 9, thereby lubricating the enlarged piston heads operating therein and also the connection of the cranks to the pistons.

The heads of the pistons are provided with removable deflectors 69, although they may be constructed integral with the pistons, to direct the incoming fuel to the head of the cylinders, said deflectors hav-

ing flaring portions 70 with openings to register with the fuel-intake ports 16 as the pistons approach the end of the power stroke, the fuel entering through said flaring portion being directed upward to the 70 head of the cylinders by a tubular portion 71. It will be obvious that a portion of the fuel will be pocketed in the deflector 69 and carried with the piston to the sparking points of the plug 49 assuring a rich 75 mixture at said points which will be readily fired.

The operation of my improved engine is substantially as follows: Assuming the pistons to be in the positions shown in Fig. 1, 80 with a charge of fuel compressed in the combustion and fuel-pumping chambers of cylinder a, combustion having taken place in cylinder b and a power stroke imparted to the piston, the piston being at the end of 85 its power stroke with the burnt gases exhausting from the combustion chamber and the compressed fuel from chamber d of cylinder a being injected through the chamber 14 in the fuel chest F through the intake 90 port 16 into the combustion chamber c of cylinder b, the valve 24 being in the position shown in Fig. 4 closing both the ports 28, 29 in the valve chest and cutting off both chambers d from the source of fuel supply. During 95 the succeeding 90 degrees of revolution of the crank shaft, or one-half the stroke of the pistons, the valve 24 will be oscillated to the positions shown in Fig. 5, the port 31 registering with the port 29 connecting the 100 chamber d of cylinder a with the source of fuel supply through the chamber 14, drawing in a charge of fuel, while the port 28 will be closed by the valve and the previously drawn in charge of fuel in chamber d, and 105 the charge of fuel in the combustion chamber c previously injected from the fuel chamber d of cylinder a, being compressed in cylinder b. During the next 90 degrees of revolution of the crank shaft, or the remaining 110 portion of the power stroke of piston in cylinder a and the latter portion of the fuel compression stroke of the piston in cylinder b, the valve will again assume substantially the position illustrated in Fig. 4 cutting off 115 both cylinders from the source of fuel supply, with a charge of fuel compressed in the combustion and fuel-pumping chambers of cylinder b, the burnt gases exhausting from the combustion chamber and a charge of 120 fuel drawn into the fuel-pumping chamber of cylinder a, the chamber d of cylinder b being connected up through chamber 15 in the chest F with the combustion chamber of cylinder a and the compressed charge of fuel 125 in the former chamber being injected into said combustion chamber. Combustion will now take place in cylinder b. During the initial one half movement of the piston, or 90 degrees of revolution of the crank shaft, 130

the valve 24 will assume the position shown in Fig. 6 with the port 30 communicating with the port 28 connecting the chamber *a* of cylinder *b* with the source of fuel supply, the charge of fuel in the combustion and fuel-pumping chambers of cylinder *a* being compressed. During the further 90 degrees of revolution of the crank shaft the pistons will again assume the positions shown in Fig. 1, and the valve mechanism assume the position shown in Fig. 4 with both of the fuel chambers *a* cut off from the source of fuel supply, when the cycle of operations will be repeated. As already stated during the fuel compression stroke of the pistons a charge of air will be sucked by the pistons into the chambers *e* through the valved ports 39 which will be compressed during the power strokes of the pistons and serve to force the lubricant through the ducts 55 to the valve mechanism and cylinder walls as well as ports 60 in the crank case during the power stroke of the pistons. As the pistons approach the end of the power stroke and just after the exhaust ports are uncovered and previous to the uncovering of the intake ports; said chambers *e* will be connected to the combustion chambers through the piston ports 42 and by-pass ports 43, whereby the compressed air in said chambers *e* will be injected into the combustion chambers forcing out the burnt gases and filling the combustion chambers with pure air at atmospheric pressure, and as the intake ports 16 are uncovered by the pistons the charge of fuel will enter the combustion chambers under pressure through the deflectors 69 and be directed by the portion 71 to the top of the cylinders, where it will mushroom forcing out the pure air and thereby effecting a thorough scavenging of the combustion chamber.

Variations may be resorted to within the scope of my invention, and portions of the invention may be used without others.

Having thus described my invention, I claim:

1. In a two cycle internal combustion engine, the combination of a crank case; a piston cylinder fixed to said case; fuel intake and exhaust ports in the cylinder; a crank shaft journaled in said case; and a piston in the cylinder connected to the crank shaft controlling the opening and closing of the ports, said piston separating the cylinder into a combustion chamber and a fuel pumping chamber, and said piston with the crank case constituting an air pumping and compression chamber; a port in the piston; and a by-pass port in the cylinder with which the piston port communicates to connect the air pumping chamber with the combustion chamber when the piston uncovers the exhaust port in the cylinder, substantially as and for the purpose specified.

2. The combination of a crank case separated into a pair of compartments; a crank shaft journaled therein; a pair of piston cylinders fixed to said crank case; pistons in said cylinders connected to the crank shaft; said pistons separating the cylinders into superposed combustion chambers having fuel-intake and exhaust ports adapted to be uncovered by the pistons as they approach the end of their outward strokes, and fuel-pumping chambers connected with the fuel supply and with the combustion chambers of their companion cylinders, and said piston with the crank case constituting air pumping and compression chambers having valved air-inlets; a port in the pistons; and by-pass ports in the cylinders with which the piston ports coöperate to open communication between the combustion chambers and their associated air pumping chambers in the crank case as the exhaust ports of the combustion chambers are uncovered by the pistons and previous to the uncovering of the inlet ports in said chambers, whereby to expel the burnt gases from the combustion chambers by means of the compressed air from the air chambers.

3. In an internal combustion engine, the combination of a crank case having two compartments; a crank shaft journaled in said case; a pair of cylinders fixed to the crank case so that one compartment of the crank case will communicate with one cylinder and have no communication with the other compartment and cylinder, and each of the cylinders having an enlarged portion toward the crank case; duplex pistons for the cylinders, said pistons separating the cylinders into combustion chambers and fuel-pumping chambers, and said piston with the compartments in the crank case constituting air pumping and compression chambers; means connected with the source of fuel supply to connect the fuel-pumping chambers with the combustion chambers of their companion cylinders; valve mechanism to control the admission of fuel to the fuel pumping chambers and from the fuel pumping chambers to the combustion chambers of their companion cylinders; a port in each piston; and by-pass ports in the cylinders with which the piston ports coöperate to open communication between said combustion chambers and their associated chambers in the crank case at a predetermined point in the power strokes of the pistons whereby to inject the compressed air from the air chambers into the combustion chambers, substantially as and for the purpose specified.

4. In an internal combustion engine, the combination of a crank case having two compartments; a crank shaft journaled in said case; a pair of cylinders fixed to the crank case so that one compartment of the crank case will communicate with one cylinder and

have no communication with the other compartment and cylinder, and each of the cylinders having an enlarged portion toward the crank case; duplex pistons for the cylinders, said pistons separating the cylinders into combustion chambers having intake and exhaust ports normally closed by the pistons and adapted to be uncovered by the pistons as they approach the ends of their power strokes; and fuel pumping chambers having ports; and said piston with the compartments in the crank case constituting air pumping and compression chambers having air inlets; normally spring closed valves for said air inlets to the air chambers; means connected with the source of fuel supply to connect the fuel-pumping chambers with the source of fuel supply with the intake ports of the combustion chambers of their companion cylinders; valve mechanism to control the admission of fuel to the fuel-pumping chambers; and the charge of fuel from said latter chambers to the combustion chambers; a port in each piston; and by-pass ports in the inner cylinder walls with which the piston ports coöperate to open communication between the combustion chambers and their associated air chambers in the crank case as the exhaust ports of the combustion chambers are uncovered by the pistons, substantially as and for the purpose specified.

5. In an internal combustion engine, the combination of a crank case separated into two chambers; a crank shaft journaled in said case; a pair of cylinders fixed to the crank case and having an enlarged portion toward the crank case; pistons for the respective cylinders connected to the crank shaft, said pistons having supplemental heads to engage in the enlarged portions of the cylinders whereby the head portions of the cylinders constitute combustion chambers having fuel-intake and exhaust ports normally covered by the pistons and adapted to be uncovered by the pistons when they approach the end of their outward strokes, and the enlarged portions of the cylinders fuel-pumping chambers each having a port; a fuel chest having a pair of compartments, one compartment connected to the port of the fuel-pumping chamber of one cylinder and the fuel-intake port of the combustion chamber of its companion cylinder, the other compartment connected to the port of the fuel-pumping chamber of the other cylinder and the fuel-intake port of the combustion chamber of its companion cylinder, and each compartment having a fuel-intake port connected to the source of fuel supply; valve mechanism operated from the crank shaft, to control the admission of fuel to the compartments of the fuel chest and the fuel-pumping chambers; a port in each piston; a by-pass port in the

inner walls of the cylinders with which the piston ports coöperate to connect the combustion chambers with their associated air chambers, substantially as and for the purpose specified.

6. In an internal combustion engine, the combination of a crank case separated into two compartments; a crank shaft journaled in said case; a pair of cylinders fixed to, and having an enlarged portion toward, the crank case; pistons for the respective cylinders connected to the crank shaft, said pistons having supplemental heads to engage in the enlarged portions of the cylinders whereby the head portions of the cylinders constitute combustion chambers having fuel-intake and exhaust ports adapted to be uncovered by the pistons as they approach the end of their outward strokes, and the enlarged portions of the cylinders fuel-pumping chambers each having a port and said pistons with the compartments in the crank case constituting air pumping and compression chambers; a fuel chest having a pair of compartments, one compartment connected to the port of the fuel-pumping chamber of one cylinder and the fuel-intake port of the combustion chamber of its companion cylinder, the other compartment connected to the port of the fuel-pumping chamber of the other cylinder and the fuel-intake port of the combustion chamber of its companion cylinder, and each compartment having a fuel-intake port; a valve chest having an intake port connected to the source of fuel supply and having a pair of outlet ports communicating with the intake-ports of the compartments in the fuel chest; an oscillatory valve in said chest to alternately open and shut off communication between the chambers of the fuel chest and the source of fuel supply; means to operate the valve from the crank shaft; a port in each piston; and a by-pass port in each cylinder with which the piston ports coöperate when the pistons approach the end of their power strokes to connect the combustion chambers with the air chambers, substantially as and for the purpose specified.

7. An internal combustion engine, comprising a pair of cylinders; a crank case having a pair of separate compartments; pistons to work in the cylinders, said pistons separating the cylinders into combustion chambers and fuel pumping chambers, and said pistons with the chambers in the crank case constituting air pumping and compression chambers; a port in each piston; a by-pass port in each cylinder with which the piston ports coöperate to connect the combustion chamber of a cylinder with its associated air chamber; a fuel chest having a pair of compartments, one compartment connected to the port of the fuel-pumping

chamber of one cylinder and the fuel-intake port of the combustion chamber of its companion cylinder, the other compartment connected to the port of the fuel-pumping chamber of the other cylinder and the fuel-intake port of the combustion chamber of its companion cylinder, and each compartment having a fuel-intake port; a tubular valve chest connected at one end to the source of fuel supply and having a pair of outlet-ports communicating with the intake-ports of the chambers in the fuel chest; a valve in said chest to alternately open and shut off communication between the chambers of the fuel chest and the source of fuel supply, comprising a tubular member mounted to oscillate in the valve chest, said member being open at one end and connected therethrough at all times with the source of fuel supply, and a pair of ports in the side wall of said valve adapted to alternately register with the outlet-ports of the valve chest; and means to operate the valve from the crank shaft; and by-pass ports 25 in the pistons and cylinders which are adapted to be placed into communication when the pistons approach the end of their outward strokes to connect the combustion chambers with their associated air chambers 30 in the crank case, substantially as and for the purpose specified.

8. An internal combustion engine, comprising a pair of cylinders; a crank case having a pair of separate compartments; pistons to work in the cylinders, said pistons separating the cylinders into combustion chambers and fuel pumping chambers, and said pistons with the chambers in the crank case constituting air pumping and 35 compression chambers; a port in each piston; a by-pass port in each cylinder with which the piston ports coöperate to connect the combustion chamber of a cylinder with its associated air chamber; a fuel chest having a pair of compartments, one compartment connected to the port of the fuel-pumping chamber of one cylinder and the fuel-intake port of the combustion chamber of its companion cylinder, the other compartment connected to the port of the fuel-pumping chamber of the other cylinder and the fuel-intake port of the combustion chamber of its companion cylinder, and each compartment having a fuel-intake port; a valve chest connected 40 to the source of fuel supply and having a pair of outlet-ports communicating with the intake ports of the fuel chest; a tubular oscillatory valve in said chest open at one end and connected therethrough with the source of fuel supply; a pair of ports in the side wall of the valve adapted to be alternately placed in communication with the ports in the valve chest to open and shut off communication between the chambers of the fuel chest and the source of fuel supply; means 45

to operate the valve from the crank shaft, comprising an eccentric disk on the crank shaft, a strap surrounding said disk, a crank on the valve, and a rod connecting the strap with the crank of the valve; and by-pass ports in the pistons and cylinders which are adapted to be placed into communication when the pistons approach the end of their outward strokes to connect the combustion chambers with their associated air chambers in the crank case, substantially as and for the purpose specified. 75

9. An internal combustion engine, comprising a crank case having two compartments each of which is provided with an air inlet; spring-influenced valves normally closing said inlets; a crank shaft journaled in said case; a pair of cylinders fixed to the crank case so that one compartment will have no communication with the other compartment and cylinder, each of the cylinders having an enlarged portion toward the crank case; pistons for the respective cylinders connected to the crank shaft, said pistons having supplemental heads to engage in the enlarged portions of the cylinders whereby the head portions of the cylinders constitute combustion chambers having fuel-intake and exhaust ports uncovered by the pistons as they approach the end of their outward strokes, the enlarged portions of the cylinders fuel-pumping chambers having a port, and the compartments in the crank case air pumping and compression chambers, the suction of the pistons during the fuel compression stroke unseating the valves in the crank case and drawing in a charge of air and during the power stroke compressing said air in the crank case below the pistons; a fuel chest having a pair of compartments, one compartment connected to the port of the fuel-pumping chamber of one cylinder and the fuel-intake port of the combustion chamber of its companion cylinder, the other compartment connected to the port of the fuel-pumping chamber of the other cylinder and the fuel-intake port of the combustion chamber of its companion cylinder, and each compartment having a fuel-intake port; a tubular valve chest connected at one end to the source of fuel supply; a pair of outlet ports in said chest communicating with the intake ports of the fuel chest; an oscillatory valve in said chest to alternately open and shut off communication between the chambers of the fuel chest and the source of fuel supply, comprising a tubular member open at one end and connected therethrough with the source of fuel supply, and a pair of ports in the side walls of said valve adapted to alternately register with the outlet ports of the valve chest; and means to operate the valve from the crank shaft, comprising a crank connected to the valve an eccentric disk on the crank shaft, a 80 85 90 95 100 105 110 115 120 125 130

strap surrounding said disk, and a rod connecting said strap with the crank of the valve; by-pass ports in the cylinders; and ports in the pistons communicating with the 5 by-pass ports as the exhaust ports are uncovered by the pistons whereby the compressed charge of air in the air chambers is injected into the combustion chambers substantially as and for the purpose specified.

10. In an internal combustion engine, the combination of a crank case having a partition to separate the case into two compartments; a crank shaft journaled in said case; a pair of cylinders fixed to the crank case; 15 duplex pistons for the respective cylinders connected to the crank shaft, said pistons separating the cylinders into combustion and fuel pumping chambers, and with the crank case constituting air pumping and 20 compression chambers; means to connect the fuel pumping chamber of one cylinder with the combustion chamber of its companion cylinder; valve mechanism to control the admission of fuel to the fuel pumping 25 chambers; by-pass ports in the inner walls of the combustion chambers; and ports in the pistons coöperating with the by-pass ports to inject the compressed air from the air chambers into their associated combustion 30 chambers as the pistons approach the end of the power stroke, substantially as and for the purpose specified.

11. A two cycle internal combustion engine, comprising combustion, fuel pumping and compression, and air pumping and compression chambers; means to connect the fuel pumping with the combustion chambers; a piston to work in the combustion and fuel pumping chambers; 40 a port in the piston; and a by-pass port in the combustion chamber with which the port in the piston coöperates to connect the air pumping chamber with the combustion chamber as the piston approaches the end of its power stroke, substantially as and for the purpose specified.

12. A two-cycle internal combustion engine, comprising a pair of combustion chambers, a pair of fuel-pumping chambers, and 50 a pair of air pumping and compression chambers; pistons working in the fuel-pumping and combustion chambers; means connected to the source of fuel supply to cross connect the fuel-pumping chambers 55 with the combustion chambers; valve mechanism to alternately open and shut off communication between the pumping chambers and the fuel supply; a port in the piston; and by-pass ports in the combustion chambers to connect the air-pumping chambers 60 with the combustion chambers as the pistons approach the end of their power strokes.

13. An internal combustion engine comprising a cylinder; a crank case; a crank shaft journaled therein; a duplex piston

working in the cylinder and connected to the crank shaft, said piston separating the cylinder into a combustion chamber having fuel-intake and exhaust ports and a fuel-pumping chamber having a port, and said 70 pistons with the crank case constituting an air pumping and compression chamber having a normally spring closed valved air inlet; valve mechanism to control the charge of fuel to the fuel pumping chambers; and 75 by-pass ports in the piston and combustion chamber to open communication between the air-pumping chamber and the combustion chamber when the piston approaches the end of its power stroke; said piston during the compression of fuel in the combustion chamber compressing a charge of fuel in the fuel pumping chamber and unseating the valve in the air chamber and drawing a charge of air therein, and during the power 80 stroke drawing in a charge of fuel into the fuel pumping chamber and compressing the air in the air chamber which was drawn therein during the compression stroke in the combustion chamber, which compressed air 85 is injected into the combustion chamber through the by-pass ports in the piston and combustion chamber as the piston approaches the end of its power stroke and uncovers the exhaust port of the combustion 90 chamber, substantially as and for the purpose specified.

14. An internal combustion engine, comprising a crank case having a partition to separate it into two compartments; a crank 100 shaft journaled therein; a pair of cylinders each cylinder comprising a pair of superposed sections, the lower sections having flanges whereby they are supported upon the crank case and coöperate with the partitions therein to separate the crank case into two compartments, and provided with normally spring-closed valved air inlets, the upper sections being of less diameter than 105 the lower sections and projecting thereinto and provided with a flange whereby they are supported upon the lower sections; tie-

rods passing through the flanges of the cylinder sections and whereby they are secured to the crank case; pistons connected to the crank shaft to operate in the cylinders, each piston having a supplemental head to engage in the lower cylinder section, said pistons separating the cylinders so that the upper sections constitute combustion 110 chambers having fuel-intake and exhaust ports, and the lower sections fuel-pumping chambers having ports, and said pistons with the compartments in the crank case constituting air pumping and compression 115 chambers with the valved air inlets in the lower cylinder sections communicating therewith; a chest having a pair of chambers connected to the source of fuel supply to cross connect the fuel-pumping chamber of one 120

125

130

cylinder with the combustion chamber of its companion cylinder; valve mechanism to control the admission of fuel to the fuel-pumping chambers; a port in each piston; 5 and by-pass ports in the upper cylinder sections to connect the air chambers with the combustion chambers of the same cylinder

as the pistons approach the end of the power stroke.

WILLARD IRVING TWOMBLY.
